LIGHT SIGNAL

Original Filed Jan. 25, 1922

FIG. 1.

UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

LIGHT SIGNAL

Original application filed January 25, 1922, Serial No. 531,588. Divided and this application filed June 29, 1927. Serial No. 202,357.

This invention relates to light signals in general and especially to signals of this kind for railway signaling purposes.

The present application is a division of application 531,588 filed January 25, 1922.

The principal object and purpose of the present invention is the provision of a signal particularly adapted to receive an incandescent lamp which has a concentrated filament and is of a construction in which its filament is located in a predetermined and fixed relation to the base and its anchoring pins.

Other objects and advantages will appear as the description progresses.

In describing the invention in detail, reference will be made to the accompanying drawings, in which:

Fig. 1 is a fragmentary sectional elevation of one form of light signal embodying the present invention;

Fig. 2 is a sectional view taken on the line 2-2, Fig. 3 viewed in the direction of the arrows;

Fig. 3 is a sectional view taken on the line 3-3, Fig. 2, viewed in the direction of the arrows.

In general the present invention comprises a casing C, a light concentrating unit U, such as a doublet lens combination and a detachable lamp supporting pedestal P.

More specifically, the invention comprises a casing C provided with a large circular opening in its front wall. The casing has bolted thereto a flanged pipe coupling 5 by which the casing may be supported on the usual signal pole 6.

In the large circular opening is supported a lens barrel 7 by screws 8. The outer end of the lens barrel is provided with a circular lens seat 9 supporting a large lens 10. This lens is held in place by a retaining ring or bezel ring 11, having a semi-circular flange 12 to which is bolted a shield 13. The inner end of the barrel 7 is provided with a similar lens seat 14 for receiving the small lens 15 of the doublet combination. This lens 15 is held in place by a retaining ring 16 which is fastened by suitable means, screws 17 being shown in the present instance. Both lenses

are provided with suitable yieldable material between them and their respective retaining rings, to serve as cushions. These lenses are of a design such that a very large solid angle of light may be refracted into a single beam of light of the desired spread. For the purposes of convenience the point at which the concentrated light source must be located, in order to produce the desired light beam, will be referred to as the "focal point of the combination" or "the focus", and this point is very near the inner lens.

An opening or socket is provided at the bottom of the casing to receive the detachable lamp supporting pedestal or adapter P. This pedestal comprises a standard 18 having a flange 19 at the bottom, through which screws pass into the bottom of the casing to rigidly and accurately support the same. The neck of the standard is provided with a split insulating collar 20 riveted thereto. Contact straps 21 are fastened to the insulating collar 20 by screws 22 from which wires 23 lead to the socket or receptacle 24 mounted on the top of the standard. This socket 24 is of the usual bayonet type construction, but is so mounted with respect to the flange 19 of the standard, that the concentrated filament 25 of a standardized (precision) lamp 26 carried by the socket shell is located at the focal point of the lens combination. The object to be obtained by locating the socket shell accurately with respect to the casing, and in turn to the lenses, is to facilitate interchangability of lamps, and in each instance to properly locate the concentrated filament without further adjustment.

Adjacent to the pedestal P is an insulating block 27 forming part of a separable connector and having binding posts 28 and two upstanding spring contact fingers 29 constructed and arranged to bear against the contact straps 21 (see Figs. 2 and 3). This insulating block 27 is provided with suitable binding posts 30 for connecting the contact straps with a source of energy. The object in providing the readily detachable means for supporting the lamp pedestal or adapter P and the cooperating spring contact fingers, is to facilitate the changing of lamps when broken or burnt out.

Having thus described the invention, what I desire to secure by Letters Patent, is:—

A light signal comprising; a casing having an opening in one wall, an optical device in said opening, a second opening in the casing, a support carrying an incandescent lamp adapted to be fastened in said second opening so that the lamp is disposed within the casing and the second opening is closed by said support, and a separable connector comprising insulated laterally biased spring clips located on the casing and lateral contacts located on the support for conducting current to said lamp.

In testimony whereof I hereto affix my signature.

WINTHROP K. HOWE.
